UNITED STATES PATENT OFFICE.

CARL MICHELSSEN, OF ROSTOCK, GERMANY.

APPARATUS FOR BOOKKEEPING.

Application filed January 15, 1924. Serial No. 686,434.

To all whom it may concern:

Be it known that I, CARL MICHELSSEN, a citizen of Germany, residing at Rostock, in the State of Mecklenburg, Germany, have 5 invented certain new and useful Improvements in Apparatus for Bookkeeping; and I do hereby declare the following to be a full, clear, and exact description of the invention, such as will enable others skilled in the art 10 to which it appertains, to make and use the same.

My invention relates to improvements in the method of and apparatus for bookkeeping, and the object of the improvements is 15 to provide a method ensuring the correct entry of commercial transactions by simultaneously making an original and a copy of the registrations on the day-book and the individual accounts by means of a typewriter machine. With this object in view 20 I make a continuous record on an original entry sheet representing the day-book and individual records on sheets of paper, cards or the like representing the account books, 25 said individual sheets of paper or cards being placed on or below the original entry sheet together with carbon paper for making a carbon copy. In order that the items 30 entered on the individual account sheets be simultaneously entered in the correct columns of the original sheet or day-book the original sheet and the account sheets are shiftable relatively to each other, and means are provided for insuring the correct relative positions of the lines and columns of the 35 sheets. Furthermore means are provided whereby new sheets placed on the original sheet or day-book are brought into the correct positions relatively to the original 40 sheet, so that the items are entered on the original sheet at the correct places.

In my improved system special notes, 45 communications, and the like may be made when entering items on the original sheet and the sheets receiving the accounts, designed to be mailed to other parties or firms for informing the same of the registrations regarding the same, which informations are automatically printed when writing 50 on the day-book and account sheets, for which purpose the account sheets or cards are equipped with sheets placed below the same so that copies of the record are made thereon by means of carbon paper.

55 In carrying out the method I make use of a typewriting machine provided with a

plane platen or writing plate. The machine is equipped with stationary printing mechanism and a carriage movable in the direction of the lines and carrying a plane 60 platen which is movable transversely of the lines for printing on the sheets or cards placed thereon. An important feature of my improved typewriting machine is that it permits visible writing. Other features 65 of the improved machine adapting the same to my improved method of book-keeping will appear from the following description.

In order that my invention be clearly understood my improved typewriting machine has been shown in the accompanying drawings, in which the same reference characters have been used in all the views 70 to indicate corresponding parts. In said drawings,—

Fig. 1, is an elevation of the machine,

Fig. 2, is a plan view,

Figs. 3 and 3^a, show a section taken on the line III—III of Fig. 1, and

Fig. 4, is a plan view of the horizontal 80 platen or writing plate showing the means for adjusting the sheets of paper or cards thereon.

In my improved method of book-keeping by means of a typewriting machine entries 85 are simultaneously made on an original entry sheet representing for example a day-book, and on exchangeable sheets or cards adapted to be combined into account books. The original sheet and the account sheets 90 are simultaneously printed by means of carbon paper, the account sheets being placed on or below the original sheet. The entries are made in the correct columns, and the items are automatically summarized, 95 so that after each entry the totals may be printed on the original sheet as well as on the account sheet or sheets. In some cases the account sheets are provided with additional sheets adapted to be printed simultaneously therewith by means of carbon paper or in any other suitable way, which may be used for example for sending communications, statements of account, and the like to the customer.

The aforesaid and other commercial transactions are written by means of a typewriting machine provided with novel means adapting the same to the object aimed at.

In the example shown in the figures my improved typewriting machine comprises

a frame A provided with legs B for supporting the same on a table. On the frame A a carriage C is guided which carries the platen, and it provides a support for the levers, key lever mechanism for operating the type levers, and the line and letter spacing mechanisms, parts of which are mounted on the frame A. At the rear end of the frame A uprights E are mounted, which provide a support for mechanical operating mechanism D, and which support a subsidiary frame F on which the ribbon spools G, the type segment H and the mechanism for operating the ribbon feeding mechanism and the type levers are mounted.

At the front side of the machine and at the rear of the key board I a guide rail 1 is mounted on the frame A, and at the rear side of the machine and in front of the uprights E a similar guide rail 2 is mounted on the frame A, which rails extend over the whole breadth of the machine. To the rail 2 a spring barrel 3 is secured the spring of which is connected by a band 4 with the carriage C for shifting the same in the direction of the line. The carriage is supported on the guide rails 1 and 2 through the intermediary of rollers 5, and it shows rails 6 providing a guide for a writing plate or platen 8 supported thereon through rollers 7. The said platen is in the form of a plane plate made from a suitable material such as rubber. It shows two pins 9 adapted to fix the original sheet 10 on the platen.

The account sheets or the like 18 are printed simultaneously with the original sheet, for which purpose they are placed on the original sheet together with sheets of carbon paper, and they are adapted to be shifted relatively to the original sheet in the direction of the lines and in the direction of the columns, according to the entries to be made thereon. For thus shifting the account sheets and permitting the same to be set in the proper positions corresponding to the lines and columns of the original sheet novel means are provided. As shown the said means consist of a frame comprising an end member 12 and U-shaped rails 12' guided in corresponding grooves 12" of the platen 8, and adapted to be retracted therefrom in the direction of the lines. The frame carries four pins 13, 14, 15, and 16 fixed thereto and a sprocket 17 having a special construction. The account sheets 18 show perforations 19 spaced from one another according to the line spaces. By means of the pins 13 to 16 the account sheets are fixed in position on the frame 12. The columns of the account sheets and the original sheet are brought into register by shifting the frame 12 relatively to the platen 8, as is shown in Figs. 2 and 4. In the position shown in Fig. 2 the frame 12 is entirely within the platen 8, and when printing

with the frame 12 in this position corresponding entries are made in the columns a, b, c, d, e, f and in the corresponding columns a', b', c', d', e', f' of the original sheet 10. As shown in Fig. 4 the frame 12 has been withdrawn from the platen in the direction of the arrow y so far that when making an entry in the column e of the account sheets the same entry appears in the column e' of the original sheet. Therefore, by shifting the frame 12 I am enabled to make the entries in any of the columns of the account sheets and the original sheet. To ensure the proper position of the entries on the individual lines the account sheets are adapted to be shifted relatively to the platen transversely of the lines. In doing this I make use of the sprocket 17. As appears from Fig. 3 the said sprocket is one of the sprockets of a sprocket wheel 20 rotatably mounted in a slide 21 and locked as against accidental displacement by a spring 22. Otherwise the slide 21 is freely movable relatively to the frame 1 in the direction of the arrow x shown in Fig. 4. As shown it is mounted in the frame 12. At its side the frame 12 is equipped with a perforated rail 23 the holes of which are spaced from one another according to the spaces of the lines, and which act on the sprocket wheel 20 in the manner of a rack. At the height of the printing point a stop 24 is provided on the carriage C, which stop is in the path of the slide 21. When shifting the carriage or the platen 8 in the direction of the arrow x the slide 21 strikes against the stop 24, and upon further movement of the platen 8 the sprocket wheel 20 is rotated by means of the perforation 23. Therefore the position of the sprocket 17 projecting through one of the perforations 23 indicates the line z to be printed upon (Fig. 4). The perforations 19 of the account sheets 18 exactly correspond to the perforations 23. Therefore it is sufficient to place the account sheet or sheets on the pins 13 to 16 in such a way that the sprocket 17 passes through the hole which corresponds to the line of the account sheet to be printed upon. For holding the account sheets and original sheet on the platen spring pressed bails 26 may be provided.

For special records a similar frame 12" provided with pins 13", 14", 15", 16", and 17" and an abutment 24" is provided at the left hand side of the platen.

The letter spacing mechanism is constructed as follows:

To the bottom side of the carriage C a rack 27 is secured which is in mesh with a gear wheel 28 secured to a shaft 29 mounted in a pair of brackets 30 rising from the frame A. To the shaft 29 a ratchet wheel 31 is secured in which the pitch of the ratchet teeth corresponds to the relative distance of

the letters. The step-by-step movement of the ratchet wheel 31 by the pull of the spring barrel 3 is controlled by pawls 32 and 33 mounted on a rocker or lever 34, the pawl 32 being movable on the said lever circumferentially of the ratchet wheel 31, while the pawl 33 is fixed thereto. The lever 34 is connected by a link 35 with a spring pressed arm 37 secured to a shaft 36, and the shaft 16 carries arms 38 having a universal bar 39 secured thereto, which bar bears on key levers 40. Therefore, when depressing a key the universal bar 39 is moved upwardly, and the movable pawl 32 is brought out of engagement with the teeth of the ratchet wheel 31, while the fixed pawl 33 is brought into engagement therewith. Therefore the pawl 32 is advanced one step corresponding to the pitch of the ratchet wheel 31. When releasing the depressed key the members 34 to 38 are returned into initial positions by the spring 11, so that the pawl 33 releases the wheel 31 and permits the same to be advanced one step according to the advanced 25 position of the pawl 32.

Line spacing is effected by shifting the platen 8. The key board shows two line spacing key levers 41 which are secured to a rock shaft 42 mounted in suitable bearings 33 provided on the frame A. At their free ends the said levers carry a bar 43 which extends over the whole breadth of the carriage 6. To the bottom side of the platen 8 and substantially to the middle thereof a rack 44 is secured the teeth of which have a pitch equal to the space of the lines. The said rack is engaged by a shifting pawl 45 and a locking pawl 46. The pawl 46 is rockingly mounted at 48 and it is acted upon by a spring 47 holding the same in engagement with the rack 44. The pawl prevents accidental movement of the platen 8 towards the key-board. The pawl 45 is jointed to a rocker 49 supported at 48, and it is acted upon by a spring 47 holding the same in engagement with the rack 44. To the rocker 49 a rod 51 is jointed which is connected with a lever 52 having a rocking support at 54. The rod 51 is acted upon by a spring 53 connected to the carriage C at 55. The lever 52 is in position for engagement by the bar 43. When depressing the key 41 the bar 43 rocks the lever 52 into the position shown in Fig. 3 in dotted lines. Thereby the rocker 49 and the pawl 45 are shifted one step towards the key board, and the spring 53 is put under tension. After releasing the key 41 the spring 53 advances the platen 8 one step and the pawl 45 is held in elevated position by a shoe 56. If it is desired to move the platen 8 by hand, the lever 52 is rocked by the key lever 41 beyond the position shown in dotted lines. Thereby the rod 51 is pulled forwardly, and an arm 50 made integral with the rocker 49 and

having a nose 50^a is rocked downwardly and towards the locking pawl 46 and the shifting pawl 45, whereby both pawls are brought out of engagement with the rack 44, and the platen can be shifted to any 70 position.

For making additions and subtractions such as are necessary in book-keeping any known or preferred mechanism may be connected with the key mechanism. Figs. 2 75 and 3 show an example which is particularly suitable in connection with the typewriting machine described herein. As appears from the drawings a plurality of calculating mechanisms K are provided in my machine, 80 which mechanisms are mounted on the carriage so as to correspond to the individual columns of the original sheet. Each calculating apparatus is equipped at its bottom part with a gear wheel 57 adapted, according to the position of the carriage C, to mesh with an elongated gear wheel 58 of an operating mechanism L. The length of the operating mechanism L is such that it can be connected by a connecting rod 59 with any 90 of the digit key levers showing the figures from 1 to 9 and the zero sign. Therefore, when depressing any of the digit keys the operating mechanism L is actuated accordingly, and the movement imparted thereto 95 is transmitted through the gear wheels 58 and 57 to the calculating mechanism.

The key levers are arranged in a manner known in the art, and at each side of the key board there is a key 41 for line spacing. 100 The bar N operates the letter spacing mechanism 27 to 39. The key board comprises two shift keys for writing small letters and capitals and special signs. The operation of the shift keys will be described hereinafter. 105

The operation of the type levers 61 by the keys of the key-board I appears from Fig. 3. Each key is secured to a key lever 40 supported at 25 and acted upon by a spring 40^a and jointed at its rear end to 110 a vertical rod 62. The top end of the said rod is jointed to a lever 63 having its fulcrum at 64 and connected by a link 65 with a type lever 61 mounted at 66. When depressing a key the lever 63 is rocked upwardly into the position shown in dotted lines so as to throw the type lever 61 forwardly and downwardly and against the platen as is indicated by the arrows 67. Elastic operation is ensured by springs 68. 115

The vertical rods 62 are connected at their bottom ends to links 69 adapted to operate the type levers by mechanical means. As appears from Fig. 3, a motor D is mounted on a bracket 70 secured to the upright E, 120 and the rotary movement of the motor is transmitted through a suitable gearing 71 to a cam shaft 72. By setting one of the links 69 into position for operation by the cam shaft the rod 62 is lifted and the type 125

lever thrown against the platen, so that for operating the type lever slight pressure on the key controlling the same is sufficient. The links 69 are jointed to the rods 62, and 5 they are adapted to be set into or out of position for operation by the cam shaft by arms 73 adapted to be operated by a bail 73^a common to all the arms. For operation 10 of the type levers by hand the links 69 are locked on the rods 62 by means of the arms 73, so that upon depression of a key the link 69 and rod 62 connected therewith are thrown upwardly. If it is desired to operate 15 the type levers from the motor D the arms 73 are rocked upwardly and out of locking engagement with the links 69. Now the links 69 are rocked with their bottom ends out of position for engagement with the cam shaft 72, the springs 40^a pulling the 20 rear ends of the key levers downwardly, as is shown in Fig. 3 in dotted lines. If now a key is depressed the link 69 is rocked with its bottom end to the shaft and into position for engagement by the cam shaft 72, 25 whereupon upward movement is imparted to the rod 62 by the said cam shaft.

Each type lever carries a plurality of types, and as shown two types 75 and 76 are disposed on each lever. To set either one of the 30 types into printing position the following mechanism is provided: Each type lever has a type head 74 pivotally mounted thereon, which head shows two types 75 and 76, and an upwardly projecting finger 77. For 35 shifting the head a bail 78 is provided which is rockingly mounted at 79 at opposite sides of the frame F, and which is equipped at both sides with an arm 80 connected by rods 81, links 82, arms 83, 84 keyed to a 40 shaft 84^a, and rods 85 with the shift key levers 60. When depressing one of the shift key levers the rods 85 are lifted and the bail 78 is rocked into the position shown in dotted lines and indicated by the character 45 78^a, in which it is in the path of the fingers 77. If now the finger of a type lever strikes against the bail, the type head 74 is turned into position with the type 76 in printing 50 position. If, however, the bail 78 is in inoperative position, the type 75 is in printing position. Upon the return movement of the type levers into vertical position the fingers 77 strike against stops 86 secured to the type basket 87. Thereby the type head 55 74 is automatically turned into normal position in which the type 75 is in position ready for printing. The type head is held in either one of its positions by a spring 88. The bail 78 is acted upon by a spring 103 60 returning the same into inoperative position when the shift key is released.

The inking ribbon 89 wound on the ribbon spools G is guided at the printing point by a ribbon vibrator 90 normally holding 65 the ribbon a suitable distance away from

the printing point for displaying the line, as is shown in Fig. 3 in full lines. When throwing the type lever against the platen the ribbon is moved towards the platen. In my machine this downward movement of the ribbon vibrator is made use of for holding the paper in position on the platen. The movement of the ribbon guide 90 is derived from the type lever operating mechanism. As shown a bail 92 is rockingly mounted at 75 opposite sides of the machine at 91, and a rod 93 secured to the rear end of the bail bears on the levers 63. The front ends 94 of the bail are in the form of leaf springs. When depressing a key and rocking the 80 lever 63 the bail 92 is moved downwardly at its front end for moving the ribbon guide towards the platen. By the elasticity of the leaf springs 94 the paper is simultaneously pressed on the platen, as is indicated in 85 Fig. 3 in dotted lines.

The ribbon feed mechanism is constructed as follows:

At its rear side each ribbon spool G is provided with a ratchet disk 95 which is 90 engaged by a pawl 97 acted upon by a spring 98 and mounted on a lever 99 having its fulcrum at 96. Each lever 99 shows a finger piece 100 adapted to be engaged by the hand of the operator for rocking the 95 pawl against the action of the spring 98 and lifting the same out of engagement with the ratchet disk 95. Thereby each ribbon spool can be connected with or disconnected 100 from the ribbon feeding mechanism. The 105 levers 99 are connected with arms 101 jointed to rods 102 connected at 103 to the bail 92. The upward and downward movement of the bail 92 is transmitted by the mechanism described to the ribbon feed mechanism 110 described to the ribbon feed mechanism.

By means of my improved typewriting machine a commercial transaction is registered as follows:

An original entry sheet 10 representing 110 for example the day-book is placed on the platen 8 on the pins 9 passing through holes made in the said sheet, and one or more account sheets 18 together with sheets of 115 carbon paper are placed on the original entry sheet, so that the lines of all the sheets are in register, the account sheets being inserted with the holes 19 on the sprocket 17 and the pins 13, 14, 15 and 16, 120 as far as the said holes and pins are in corresponding positions. Now the frame 19 is shifted inwardly or outwardly, until the columns of the account sheet or sheets to be 125 printed upon correspond to the proper columns of the original entry sheet.

Now the desired entry is made by means of the typewriting machine, which entry appears on the original sheet as well as on the account sheet or sheets. According as 130 the next entry is to be made on the same

or other account sheets, either the frame 12 is shifted into the position corresponding to the new entry, or the account sheets are removed and other sheets are placed on the 6 platen, while the original entry sheet is not removed, whereupon the account sheets are set into the proper position and the next entry is made.

While in describing the invention reference has been made to a particular construction 10 of the typewriting machine. I wish it to be understood that my invention is not limited to the construction shown in the drawings, and that various changes may be 15 made in the general arrangement of the machine and the construction of its parts without departing from the invention.

I claim:

1. A typewriting machine, comprising 20 printing mechanism, a platen adapted to have sheets placed thereon, and means adapted to have a part of said sheets fixed thereto and to be shifted therewith over the surface of the platen.

2. A typewriting machine, comprising 25 printing mechanism, a plane platen adapted to have sheets placed thereon, and a frame shiftable on said platen in the direction of the lines and provided with means for fixing a part of said sheets thereto.

3. A typewriting machine, comprising 30 printing mechanism, a plane platen adapted to have sheets placed thereon, sheets provided with a series of perforations disposed transversely of the lines and corresponding to the line spaces, and pins on said platen in position for engagement with said perforations.

4. In a typewriting machine, the combination 40 with the writing mechanism, of a carriage, letter spacing mechanism therefor, a platen shiftable on the carriage in a direction transversely of the letter spacing movement thereof, means for holding a sheet on said platen, and a member adapted to be moved together with the platen for indicating the line being printed.

5. In a typewriting machine, the combination, with the writing mechanism, of a 50 platen, means for moving the platen for line spacing, and indicating means movable together with the letter spacing movement of the platen for indicating the line being printed.

6. In a typewriting machine, the combination, with the writing mechanism, of a carriage, letter spacing mechanism therefor, a platen shiftable on the carriage in a direction transversely of the letter spacing movement thereof and formed with a rack, a sprocket wheel engaging in said rack and bodily movable on said platen, and means on said carriage for stopping the bodily movement of the sprocket wheel.

7. A typewriting machine, comprising

printing mechanism, a plane platen adapted to have sheets placed thereon, a frame shiftable on said platen in the direction of the lines and provided with means for fixing a part of said sheets thereto and with a rack 70 disposed transversely of the lines, a sprocket wheel engaging in said rack and bodily movable on said frame, and a stop on said carriage in the path of the sprocket wheel for arresting the bodily movement thereof. 75

8. A typewriting machine, comprising printing mechanism, a plane platen adapted to have sheets placed thereon, a frame shiftable on said platen in the direction of the lines and provided with means for fixing a 80 part of said sheets thereto and with a rack disposed transversely of the lines, a slide bodily movable on said frame transversely of the lines, a sprocket wheel mounted on said slide and engaging in said rack, and a stop on said carriage in the path of the slide for arresting the same.

9. A typewriting machine, comprising printing mechanism, a plane platen adapted to have sheets placed thereon, means shiftable in a plane parallel to the platen and provided with projecting pins, and a sheet formed with perforations adapted for engagement by said pins.

10. In a typewriting machine, the combination, with a frame, a carriage movable on said frame for letter spacing, and a plane platen on said carriage movable for line spacing, of type levers mounted on said frame at the rear of the carriage and rockable forwardly and downwardly for printing, key levers disposed on said frame below the carriage, and an operative connection between said key levers and type levers. 95

11. In a typewriting machine, the combination, with a frame, a carriage movable on said frame for letter spacing, and a plane platen on said carriage movable for line spacing, of type levers mounted on said frame at the rear of the carriage and rockable forwardly and downwardly for printing, key levers disposed on said frame below the carriage, and vertical rods at the rear of the carriage and connecting said key levers and type levers. 105

12. In a typewriting machine, the combination, with a frame, a carriage movable on said frame for letter spacing, and a plane platen on said carriage movable for line spacing, of type levers mounted on said frame at the rear of the carriage and rockable forwardly and downwardly for printing, key levers disposed on said frame below the carriage, levers connected with said type levers and extending rearwardly therefrom, and an operative connection between said rearwardly extending levers and key levers. 110

13. In a typewriting machine, the combination, with a frame, a carriage movable 120

on said frame for letter spacing, and a platen 10
posed on said frame below the carriage, and
platen on said carriage movable for line
spacing; of type levers mounted on said
frame at the rear of the carriage and rock-
able forwardly and downwardly for print-
ing, springs tending to retract the type
levers away from the platen, key levers dis-

posed on said frame below the carriage, and
an operative connection between said key
levers and type levers.

In testimony whereof I hereunto affix my
signature.

CARL MICHELSSEN.
